UNITED STATES PATENT OFFICE.

WILLIAM H. MCKISSICK, OF TULSA, OKLAHOMA.

MEANS FOR AND METHOD OF DRAINING WELL TUBING PREPARATORY TO PULLING SAME.

Application filed June 28, 1922. Serial No. 571,502.

To all whom it may concern:

Be it known that I, WILLIAM H. MCKISSICK, a citizen of the United States, residing at Tulsa, in the county of Tulsa and 5 State of Oklahoma, have invented a certain new and useful Improvement in Means for and Methods of Draining Well Tubing Preparatory to Pulling Same, of which the following is a full, clear, and exact description, reference being had to the accompanying drawings.

This invention, like that constituting the subject matter of my Patent 1,442,960, Jan. 23, 1923, relates generally to apparatus for 15 use in deep well operations, the present invention having to do more particularly with the method of draining well tubing preparatory to pulling the same, and to improved means for practicing said method.

20 In the working of deep wells, such as oil wells, it becomes necessary at comparatively frequent intervals to pull the pump tubing for the purpose of repairs, as for the replacement of the pump cups or pump 25 valve, or the renewal of the standing valve. In the normal operation of the pump, the standing valve opens as the pump piston ascends, letting into the working barrel and tubing a quantity of liquid according to the 30 lift of the piston, and closes when the piston ceases to ascend and remains closed during its descending stroke. When it is desired to inspect or repair the parts above referred to, the string of sucker rods 35 (which carries at its lower end the pump piston) is first withdrawn from the tubing, and then the tubing is pulled. Now, unless the liquid within the tubing is first drained back into the well, it results in the 40 loss of this liquid and in the saturation of the equipment, such as the bull ropes and belting. Furthermore, and very obviously, it takes considerably longer to pull "wet" 45 tubing than tubing from which the liquid has been drained.

It is the fundamental purpose of my invention to provide a comparatively simple method, and an efficient and particularly convenient means for draining the liquid 50 from the tubing prior to withdrawing it from the casing, eliminating the difficulties above set forth and saving the liquid which is otherwise lost and avoiding the great in-

convenience, annoyance and waste of time incident to the pulling of "wet" tubing. 55

Hereinafter, unless otherwise specified, the term tubing will be understood to include the working barrel that is applied to the lower end of the tubing proper and wherein the piston operates. The working 60 barrel is of somewhat lesser internal diameter than the tubing proper, as is readily understood by those familiar with the art.

The method comprehended by the invention consists in pulling the tubing into the 65 well casing, or until its lower end reaches the fluid level, then unseating a valve situated at the lower end of the tubing, allowing the liquid that is within the tubing to drain back into the well on top of the liquid 70 that has accumulated therein, thereby overcoming the possibility of causing a turmoil or commotion in the sand, an action to be carefully guarded against, as will be appreciated by those acquainted with well 75 work.

In the accompanying drawing I have illustrated two embodiments of my invention as it pertains to the means for carrying out the foregoing method. Fig. 1 is 80 a longitudinal sectional view through a working barrel equipped with a standing valve incorporating my invention and showing thereabove the pump piston; Fig. 2 is a view similar to Fig. 1 showing the pump 85 piston removed and a weight coacting with the standing valve in such manner as to unseat it for draining purposes; and Fig. 3 shows a pump tubing equipped with another form of the draining means, the valve 90 whereof is shown as unseated by a weight that has been dropped into the tubing.

In Figs. 1 and 2 the working barrel is designated 1, and this barrel is situated at the lower end of the pump tubing (not 95 shown) in accordance with common practice. The working barrel is somewhat less in diameter than the tubing, the same having an internal diameter of approximately one and three-fourths inches when used 100 with a two-inch internal diameter tubing and to which it has connection through a suitable coupling. The barrel 1 has applied to its threaded lower end a shoe 2 which supports the standing valve assembly 3. 105 This assembly comprises a tubular body 4

which is shown as surrounded by compressible material 5 which, in practice, may consist of a plurality of leather washers. The upper end of the body portion 4 is threaded 5 for the application of a cage 6 which retains the ball valve 7 in operative relation to the valve seat incorporated in a member 8 that is clamped in place between the cage 6 and the body portion 4. The cage 6 is 10 reduced in diameter at its upper end and terminates in a pin 10, and pivoted within the cage, upon a pintle 11, is a lever 12. Ordinarily this lever reposes in the position shown in Fig. 1 with its lower end removed 15 from the ball space of the cage, so that the ball 7 has freedom of movement, the lever being retained in such position through the weight of its enlarged upper end. Where the upper end of the lever protrudes 20 beyond one side of the reduced portion of the cage 6 it is inclined as shown at 13 to provide a cam surface for a purpose which I shall presently explain.

Operating within the barrel a suitable 25 distance above the standing valve is a pump piston 15 of usual type, the same involving cups 16 and a ball check valve 17 that is confined within a cage 18. On the pin 19 of the piston is screwed the lower end of a 30 string of sucker rods by means of which the piston is reciprocated, the coupling of the lowermost rod being indicated at 20.

When it becomes necessary to pull the tubing for reasons already related, the piston 35 15, by means of the sucker rods, is withdrawn from the barrel into the larger diameter tubing and thence upwardly through the tubing from which it is finally removed, leaving in the tubing and barrel the column 40 of liquid that was being elevated by the pump. The tubing is then raised until its lower end reaches the fluid level within the well, as hereinbefore explained, and in a manner which will be readily understood by 45 those familiar with deep well operations, and a tubular weight 25 is then dropped into the tubing. The weight descends therein (the liquid passing through the bore of the weight during the descent) until it reaches 50 the lower end of the barrel and engages over the upper end of the standing valve assembly and strikes the cam surface 13 of the lever 12, rocking the lever upon its pivot to the position shown in Fig. 2, causing the 55 lower end of the lever to lift the ball 7 off its seat which allows the liquid to flow back into the well. The empty tubing may now be readily pulled.

The foregoing form of the invention, 60 which provides for a complete draining of the tubing to the very bottom of the working barrel, is adapted for use where there is practically no sand present in the oil. It is found, however, that with many wells a 65 considerable amount of sand is pumped into

the tubing with the liquid and then when it is desired to pull the tubing the sand settles down about the standing valve and makes it impossible to trip the ball thereof as in the foregoing embodiment. 70

The form of my invention illustrated in Fig. 3 is adapted to situations where sand enters the tubing with the liquid. According to the present form of the invention I provide a drain valve which may be placed 75 anywhere within the tubing, say 50 to 100 feet above the pump, depending upon the proportions of sand and liquid.

In Fig. 3, separated sections of the tubing are designated 30 and 31 and to the lower 80 end of the former section is screwed the casing member 32 of my drain valve within an offset 33 whereof is pivoted, upon a pin 34, a trigger 35 which is adapted to engage and remove from its seat the ball valve 36, the trigger being normally held away from the ball by means of its weighted end 37, the normal position of the trigger being indicated in dotted lines. A seat for the ball 36 is shown as provided by the inner end of a 85 tube 38 that is threaded upwardly through a tapped hole in the lower side of the offset 33. Screwed into the lower end of the casing 32, in axial alignment with the tubing section 30, is a nipple 40. The internal diameter of this nipple is somewhat less than that of the tubing, it being found that a nipple which is $1\frac{3}{4}$ inches inside diameter is suitable for use with the standard two inch internal diameter tubing. The upper end 90 of the nipple, therefore, constitutes a shoulder 41 that is a slight distance below the plane of the trigger 35. The nipple 40 has connection, through a coupling 43, with the lower tubing section 31, and as will be 95 readily understood, the working barrel of the pump is applied to the tubing at a suitable distance below this point.

In the use of this form of the invention, 100 after the pump piston has been withdrawn, the tubing is elevated until the drain valve is at about the fluid level within the well, when a tubular weight 45 is dropped into the tubing, the weight descending therein until it engages the shoulder 41. When in 105 this position, the weight retains the trigger 35 in the full line position wherein it engages the ball 36 to hold it off its seat, allowing the liquid within the tubing to drain back into the well. The weight 45 is of a 110 diameter between the internal diameters of the nipple and tubing, so that it will be sustained by the shoulder 41, and leave ample room between it and the wall of the tubing to permit the liquid to flow freely past it. 115

The importance of the invention, especially as used in connection with oil wells, will be more fully appreciated when it is pointed out that a barrel of oil weighs 297 lbs.; that there are approximately 4 barrels of oil 120

to 1000 feet of 2" tubing and approximately 9 barrels of oil to 1000 feet of 3" tubing, and that oil wells of from three to four thousand feet deep are not uncommon. 5 From this it will be seen how much more work is imposed upon the rigging in pulling "wet" tubing than in pulling tubing from which the oil has been drained. One is also reminded of the great loss of oil incident to 10 the pulling of "wet" tubing. Also, much time is saved by draining the tubing before pulling it, as naturally the work is greatly hampered by the presence of the oil.

I would also call attention to the fact that 15 my invention is applicable to standard practice, and should not be confused with draining means for pumps made necessary by special equipment involving tubular pump rods, liquid sealed pump pistons, etc., and 20 wherein no provision is made for draining the tubing proper preparatory to pulling it.

Having thus described my invention, what I claim is:

1. In combination with well tubing 25 wherein a pump piston is adapted to operate, a standing valve situated at the lower end of said tubing, means associated with said valve for unseating it, a part shielding said means from contact by the piston 30 should the latter be depressed into engagement with the standing valve, and a member adapted to be lowered into the tubing upon the withdrawal therefrom of the piston for engaging and actuating said means 35 thereby to unseat the standing valve and allow the liquid in the tubing to drain back into the well.

2. In combination with well tubing with- 40 in which a pump piston is adapted to operate, a valve situated at the lower end of said tubing, a lever pivotally supported in operative relation to said valve and adapted when swung on its pivot to unseat the valve, and a member adapted to be lowered into 45 the tubing upon the withdrawal therefrom of the piston and designed to engage and rock said lever on its pivot.

3. In combination with well tubing with- 50 in which a pump piston is adapted to operate,

ate, a standing valve situated at the lower 50 end of said tubing, a lever pivotally sup- ported in operative relation to said valve and adapted when swung on its pivot to unseat the valve, a part shielding said lever from contact of the piston should the latter be 55 depressed into engagement with the stand- ing valve, and a member adapted to be lowered into the tubing upon the with- drawal therefrom of the piston and designed to engage and rock said lever on its pivot. 60

4. In combination with standard well tub- 65 ing of the class described within which a pump piston is adapted to operate, a stand- ing valve situated at the lower end of said tubing, a lever pivotally supported in oper- 70 ative relation to said valve and adapted when swung in a given direction to unseat the valve, said lever having a cam portion, and a member adapted to be lowered into the tubing upon the withdrawal therefrom 75 of the piston and arranged to engage the cam portion of said lever and swing the same in the direction to unseat the standing valve.

5. In combination with standard well tub- 75 ing within which a pump piston is adapted to operate, a standing valve situated at the lower end of said tubing, a lever pivotally supported in operative relation to said valve and adapted when swung in a given 80 direction to unseat the valve, said lever hav- ing a cam portion, and a member adapted to be lowered into the tubing upon the withdrawal therefrom of the piston and adapted regardless of its angular position within the 85 tubing to engage the cam portion of said lever and swing the same in the direction to unseat the standing valve.

6. The herein described method which 90 consists in withdrawing the pump piston from the tubing, lifting the tubing until a valve therein is at about the fluid level in the well, opening said valve so that the contents of the tubing may flow back into the well, and pulling the empty tubing. 95

In testimony whereof, I hereunto affix my signature.

WILLIAM H. McKISSICK.
